UNITED STATES PATENT OFFICE.

FRANK HARPER, OF JACKSON, OHIO.

COOKING-STOVE.

No. 856,581.

Specification of Letters Patent.

Patented June 11, 1907.

Application filed March 2, 1906. Serial No. 303,888.

To all whom it may concern:

Be it known that I, FRANK HARPER, a citizen of the United States, residing at Jackson, in the county of Jackson and State of Ohio, have invented certain new and useful Improvements in Cooking-Stoves, of which the following is a specification.

The object of my invention is to provide an improved construction of cooking stove 10 designed to cook by means of either gas or coal fuel or both, and so constructed that its assembled parts will be compactly arranged and efficient in operation for all the various uses of which a device of this character is 15 capable.

For a full description of the invention and the merits thereof and also to acquire a knowledge of the details of construction of the means for effecting the result, reference 20 is to be had to the following description and accompanying drawings, in which:

Figure 1 is a top plan view of my improved combination stove, part of the top thereof being broken away. Fig. 2 is a vertical longitudinal sectional view.

Corresponding and like parts are referred to in the following description and indicated in all the views of the drawings by like reference characters.

My improved cooking stove is provided with a fire box 1 embodying a grate 2 and front and back wells or castings 3 and 4. Underneath the grate 2 of the fire box is located a removable ash pan 5 designed to rest 35 upon a shelf or plate 6. The fire box in the present embodiment of my invention is located at the extreme left of the body proper of the stove, as shown.

My improved cooking stove also embodies 40 a closet or receptacle 7 which is secured by rivets or the like to the body of the stove in a suspended relation and which is intended to contain a removable oven 8 which in operative relation is supported on top of the receptacle 7. In addition to this removable oven, the stove embodies a stationary oven 9 which in the present instance is located at the right hand end of the stove and is suspended 45 therein in a spaced relation from the walls of the stove body so as to provide a flue passage 10 around the oven. Between the stationary oven 9 and the fire box 1 a water coil 11 is positioned, the upper end thereof being in contiguous relation to the back wall of the 50 fire box 1. The coil 11 is located between partition walls 12 and 12^a which extend ver-

tically within the body of the stove. The partition wall 12 assists in supporting the shelf 6 and also supports the back wall or casting 4^a of the fire box. The wall 12^a is 60 provided with an opening 12^b at its upper end.

The top of the stove is provided with the usual burner openings 13, four of said openings being provided in the present instance, 65 and two of said openings are located directly over the fire box 1. It is of course understood that all of these openings are intended to be covered whenever desired, with the usual removable lids. The top of the closet or receptacle 7 is also provided with burner openings 14, that are, as shown, of the design usually employed in gas stoves. At the back of the main portion of the stove is secured a cylindrical hood 15 which is intended to contain 70 a water boiler or heater 16 and which is provided with an upward extension 17 designed for attachment to the smoke pipe or flue. The interior of the cylindrical hood 15 communicates with one end of the passage 10 by 75 means of an elbow or similar pipe connection 18, and a damper 19 governs said communication. By means of this damper a draft may be established between the outer or upper end of the flue passage 10 and the interior of 80 the hood. The said draft may be cut off whenever desired. In addition to the elbow 18, direct communication may be established between the interior of the hood and the main interior portion of the stove, by means 85 of openings 20, each of which is controlled by a damper 21.

In addition to the fire box 1, the stove embodies other heating devices. These heating devices are gas burners, and as illustrated 90 there are two of such burners, designated 22, provided for the openings 14 of the closet or receptacle 7 and underneath said gas burners 22 is located a soot tray 23 which is intended to slide into the closet upon ledges 24 95 through a side opening in the said receptacle 7. Whenever necessary the tray 23 may be withdrawn laterally and cleaned. Gas burners are also provided for the burner openings 13 in the body of the stove. These last 100 named gas burners are designated 25 and 26. The burners 25 are carried on the outer ends of tubes 27 that are fitted to telescope over the stationary branch pipes 28 radiating from a common head 29. The burners 26 105 are carried in a stationary manner on the two complementary branch tubes 28^a. The head

29 supplies all the burners 25 and 26 and is provided with an air inlet tube 30 that preferably enters the front of the stove, the gas and air being thereby mixed to produce the proper blue flame. The water coil 11 is also supplied with a gas burner 31, and a gas burner 32 is located underneath the stationary oven 9.

The partition wall 12^a near its lower end is provided with an opening which is governed by means of a damper 33 preferably operable from the front portion of the stove, and the said damper is also designed to control one end of the flue passage 10. As illustrated in the drawings, the parts are so related that the damper 33 may either be swung down to close the opening in the partition wall 12^a or may be swung up into a horizontal position against the lower left-hand corner of the stationary oven 9 to extend entirely across and cut off the flue passage 10.

From the foregoing description in connection with the accompanying drawings it is evident that my improved cooking stove may utilize either coal or gas or both as fuel. If it be desired to use coal alone, and at the same time to heat the water coil 11, the oven 9, and the boiler 16, the dampers 21 may be closed, the damper 33 dropped, and the damper 19 left open. A draft will thus be established around the upper end of the water coil, down through the adjacent portion of the flue passage 10 to heat the coil, across the bottom of the oven to heat the latter, and up through the other side of the flue passage past the damper 19 and through the elbow 18 into the hood 15 where it will heat the boiler 16 and finally pass up into the flue. When coal alone is used, the burners 25 may be slid laterally out of the way where they will not project underneath their respective burner openings 13.

It is to be understood in this description, that while the heat passes down around the coils 11, it may pass through the coils by opening damper 33, although the coils are primarily intended to be heated by gas supplied through the burner 31. If it be desired to use both coal and gas, it is obvious that this can be done by burning gas at any or all of the burners 22, 26, 31 and 32, the burners 25 being pushed back out of the way.

If it be desired to use only gas, the burners 25 are preferably drawn outwardly into proper registry with the burner openings 13 and any of the gas burners before described, lighted, according to the particular conditions existing and the particular cooking operations desired to be performed. For instance, the burners 25, and 26 may all be lighted to cook upon the burner openings 13, and the boiler 16 may be heated at the same time by opening the dampers 21, or water may be heated by lighting the burner 31.

The stationary oven may be utilized by

lighting the burner 32, or by lighting the burners 22 the removable oven 8 may be utilized, or both of said ovens may be used whenever necessary.

When gas alone is used and the burner 31 is lighted, the damper 33 may be turned into a horizontal position across the flue passage 10 in which event a draft will be established in a downward direction between the partition walls 12 and 12^a, through the opening in the latter, and along the bottom of the stationary oven 9 and up the outer side thereof, and finally through the elbow 18 into the hood 15, the heat finally escaping through the flue connection 17. And the coil 11 may also be heated when using coal as fuel, if the damper 33 be turned upwardly against the adjacent corner of the oven 9, for in this event, as the upper end of the coil is open the products of combustion will pass downwardly through the coil between the partition 12 and 12^a and thence out past the damper 33 and around the oven 10 and through the damper 19, it being understood that the latter is open.

It will be seen that I have provided an improved construction of cooking stove which embodies in the one article a useful combinations of parts that are correlated in their action so that the stove may be used under all the varying conditions arising with a device of this nature.

The same stove may be used as above set forth for either coal or gas, which is a desideratum, especially in flats or apartment houses where the utilization of space is a consideration. Whenever it is necessary to shut off the gas for the purpose of repair or the like, the fire box may be used with coal.

It is to be understood that the water coil 11 is intended to heat water for all domestic purposes and it may also be used as a supply device for hot water or steam heating systems.

Having thus described the invention, what is claimed as new is:

1. A cook stove provided with a fire box, a water coil located with its upper end contiguous to the fire box, spaced apart partition walls inclosing said water coil, one of said partition walls being provided near its upper end with an opening in communication with the upper end of the water coil and in communication with the fire box and with another opening near its lower end, an oven spaced from the walls of the stove and from the last named partition, whereby to provide a flue passage, one end of which is in communication with the fire box and with the upper opening of the partition wall, and a damper arranged to close the lower opening in the said partition wall and also to be swung up therefrom and across the flue passage above the said lower opening so as to cut-off the flue passage above said opening, whereby the draft from the fire box may be directed

around the oven, or fires through the water coil and out through the lower opening in the partition wall so as to extend across the bottom of the oven and up around the far side thereof.

- 5 2. A cook stove provided with a fire box, spaced apart partition walls contiguous to said fire box, an oven spaced from the walls of the stove and from one of the partition walls whereby to provide a flue passage, one of said partition walls being provided with an opening in its upper end in communication with the fire box and one end of the flue passage, and said wall being provided with another opening near its lower end, a damper hinged to the said partition wall and adapted to close the lower opening therein and to be swung up away from said opening into contact with the oven, so as to close that portion 10 of the flue passage above the bottom of the oven and on one side of the latter, a hood connected to the back of the stove, dampers adapted to establish communication between said hood and the far end of the flue passage 15 and also between said hood and the interior of the stove at points intermediate of the fire box and the adjacent end of the flue passage, a boiler in said hood, and a water coil between said partition walls with its upper 20 end in communication with the upper opening of the said partition wall, whereby the heat from the fire box may be directed immedi-

ately out of the same into the hood, or around through the upper opening in the partition wall through the coil, and out across the bottom of the oven, or around through the entire extent of the flue passage, after being materially directed through the upper opening of the partition wall into the water coil.

3. A cooking stove provided with a fire box, a water coil adjacent the fire box and in communication therewith, the upper end of said coil being located contiguous to and underneath the back plate of the fire box, a pair of partition walls inclosing said water coil, an oven spaced from the walls of the stove whereby to provide a flue passage with the walls of the stove and with the adjacent partition wall, said latter being provided with an opening near its upper end and also 45 with an opening near its lower end, a damper designed to close said last named opening and also arranged to be swung up against the adjacent corner of the oven whereby to cut off that portion of the flue passage above it, 50 and a gas burner mounted between the partition walls in position to directly heat said coil, as and for the purpose set forth.

In testimony whereof I affix my signature in presence of two witnesses.
